UNITED STATES PATENT OFFICE.

CHARLES LEACH, OF McCOOK, NEBRASKA, ASSIGNOR OF ONE-HALF TO
ED. L. LAYCOCK, OF SAME PLACE.

WRENCH.

SPECIFICATION forming part of Letters Patent No. 473,007, dated April 19, 1892.

Application filed November 6, 1891. Serial No. 411,082. (No model.)

To all whom it may concern:

Be it known that I, CHARLES LEACH, a citizen of the United States, residing at McCook, in the county of Red Willow and State of Nebraska, have invented a new and useful Wrench, of which the following is a specification.

This invention relates to improvements in pipe, rod, and nut wrenches; and the objects 10 in view are to provide a wrench adapted for the above applications, which is readily adjustable to accommodate various sizes of rods, pipes, and nuts and to securely grip the same when applied.

15 Various other objects and advantages of the invention will appear in the following description, and the novel features thereof will be particularly pointed out in the claim.

Referring to the drawings, Figure 1 is a perspective of a wrench constructed in accordance with my invention. Fig. 2 is a longitudinal section. Fig. 3 is a detail in perspective of the outer end of the rod and jaws.

20 Like numerals of reference indicate like parts in all the figures of the drawings.

The handle 1 of the wrench is somewhat conical externally and is provided at its lower end or base with a surrounding thickened band or portion 2. The handle is bored internally to correspond with its external appearance, and merges from an oblong recess 3 at its base to a cylindrical bore 4 at its upper end. In the bore 4 there is mounted a cylindrical feed-rod 5, the upper end of which is 25 threaded and receives an adjusting-nut 6, adapted to be manipulated by hand and to feed the rod into or withdraw it from the bore 4. The lower end of the rod is bifurcated, as at 7, and above the same is provided with a stop 8, said bifurcations being provided with bearing perforations 9.

10 designates a pair of triangular jaws having their flat edges toward each other and toothed, as shown, near their free ends, while 45 their external edges are inclined to form bearing-shoulders 11. The upper ends of the jaws are oppositely disposed to form extensions 12, the outer edges of which are inclined in opposite directions, as shown, and the inner faces 50 of which are cut away or recessed, so as to

overlap each other. These extensions are mounted between the bifurcations of the feed-rod, and a bearing-pin 13 serves as a pivotal means of connection between the jaws and rod. Between the stop upon the rod and the 55 inclined edges at the inner ends of the jaws a coiled spring 14 is interposed, the tendency of the spring being to open the jaws by pressing upon the inclined edges of the extensions at opposite sides of the pivotal connection. 60

In operation it will be seen that by loosening the nut upon the rod the same may be fed inwardly and the spring will serve to open the jaws as they are projected from the end of the handle. In this manner the jaws may 65 be spread sufficiently to engage over a bolt, rod, pipe, or nut and may be clamped thereupon by running the nut down upon the rod, thus drawing the jaws within the handle, their outer inclined faces riding against the 70 opposite walls of the recess 4 of the latter. This having been accomplished, the wrench is operated in the usual manner for rotating the object upon which its jaws are clamped.

Having described my invention, what I 75 claim is—

In a wrench, the combination, with the conical handle having the flared rectangular flattened or elongated opening at its lower end merging into the reduced cylindrical opening 80 at its upper end, the threaded bifurcated feed-rod mounted in the latter opening and provided above its bifurcated end with a shoulder 8, the triangular jaws toothed at their inner edges and having outer inclined bearing-faces and at their inner ends recessed, overlapped, and pivoted between the bifurcations of the rod and projecting beyond the same and inclined inward, and the coiled spring interposed between the inclined inner 85 ends of the jaws and the shoulder 8 of the rod, substantially as specified.

In testimony that I claim the foregoing as my own I have hereto affixed my signature in the presence of two witnesses.

CHARLES LEACH.
